UNITED STATES PATENT OFFICE.

LEON S. BRACH, OF NEW YORK, N. Y.

LIGHTNING-ARRESTER.

1,171,166.

Specification of Letters Patent.

Patented Feb. 8, 1916.

Application filed April 8, 1911. Serial No. 618,569.

To all whom it may concern:

Be it known that I, LEON S. BRACH, residing at New York, in the county of New York and State of New York, have invented certain new and useful Improvements in Lightning Arresters, of which the following is a specification.

This invention relates to lightning arresters of the type adapted for use with telephone and telegraph lines.

One of the objects of the invention is to provide a new and improved arrester, such that it will remain intact after unusual discharges, thereby preventing the line from being permanently grounded.

Another object is to so combine in a lightning arrester a high resistance insulating member and an air gap, whereby the former will protect the line, so that static discharges of moderate potential will be discharged to ground through the high resistance material without arcing and whereby unusual currents of very high potential passing over the line will be discharged to ground across the air gap, thereby protecting the line from such high potential and preventing the disarrangement or disintegration of the high resistance insulating member interposed between the line and ground.

Other objects will be in part obvious, and in part pointed out hereinafter.

The invention accordingly consists in the features of construction, combinations of elements and arrangements of parts, which will be exemplified in the construction hereinafter described, and the scope of the application of which will be indicated in the following claims.

In the accompanying drawings, wherein I have illustrated a merely preferred form of embodiment of my invention the figure illustrates such embodiment diagrammatically.

Referring now to this drawing, wherein I have illustrated a 2-point insulator, the numeral 1 denotes a suitable base member carrying the binding posts 2 and 3 of one line connection, and the binding posts 4 and 5 of another line connection.

6 indicates a binding post from which leads a wire 7 to the ground 8, which it will be noted is common to both of the line connections. Extended between the binding posts 2 and 3 is a wire 10, which includes a fuse illustrated diagrammatically at 11, and extended between the binding posts 4 and

5 is a wire 12, which includes a similarly shown fuse 13. These fuses may of course be of any approved construction.

Leading from the wire 10 intermediate its ends is a wire 14 which connects with the plate 15, between which and the opposed plate 16 is interposed a member 17 formed of high resistance material. This high resistance material may consist of a carbonium, silicon, or carbon composition held in a suitable high resistance binder, and is of course in electrical connection with the plates 15 and 16, said plates being formed of a conducting material, and wire 18 leads from the plate 16 to a wire 19 which connects with the binding post 6.

Leading from the wire 12, intermediate its ends is a wire 20, the same connecting with a plate 21, similar in all respects to plate 15 and between this plate and a similar plate 22, is a high resistance material 23; plate 22 being connected by means of wire 24 with the common wire 19.

Plates 15 and 16, in the present instance, are provided with opposed points 25 and 26, which extend toward each other but terminate short of contact so as to form an air gap therebetween. Similarly, the plates 21 and 22 are provided with the contact points 27 and 28, between which is formed an air gap. All of the plates 15, 16, and 21, 22, may be readily bent, or otherwise manipulated to adjust the points 25, 26, and 27, 28, farther apart or closer together, so as to determine the amount of voltage at which the air gap will break down.

Having thus described the construction of this embodiment of my invention, the operation thereof may now be understood. By reason of the provision of the high resistance material between the line and ground, relatively small static discharges coming over the line are taken care of without arcing; since such discharges will pass through the high resistance material in preference to the air gap. Therefore, since there is no arc, there is no tendency for particles of carbon or other material to become dislodged and form a permanent connection between the line and ground. However, when unusual discharges of relatively high potential are discharged between the line and ground, such discharges will take place through the air gap provided between the opposed contact points 25, 26 and 27, 28, leaving the high resistance material intact,

and thereby insuring against a permanent ground connection between the line and ground. It will accordingly be seen that I have provided means which, while fully protecting the line against discharges of either high or low potential, will, nevertheless, be little likely to become disarranged, and which will require a minimum exercise of care and attention, and at the same time is of a very simple construction.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense. It is also to be understood that the language used in the following claim is intended to cover all of the generic and specific features of the invention which as a matter of language, might be said to fall therebetween.

Having thus described my invention, what I claim as new and desire to secure by Letters Patent, is:

1. In a lightning arrester, the combination with a line and ground connection therefor, of a member of relatively low conductivity interposed between said line and ground, and spaced conductors providing an air gap in multiple with said low con-

ducting member, said spaced conductors comprising a pair of members at least one 35 of which is bendable whereby to adjust the degree of the resistance offered by the air gap and consequently for varying the maximum load to be placed upon the interposed low conducting member. 40

2. In a lightning arrester, the combination with a line and a ground connection therefor, of a block of material of relatively low conductivity interposed between said line and ground having oppositely disposed substantially parallel faces, a pair of plates of conducting material, one engaging each of said faces and having parts extending substantially straight therefrom so that their outer ends are spaced apart to provide an air gap in multiple with said interposed block of material, and at least one of said plates being bendable whereby the outer ends of said plates may be moved toward or away from each other for varying 50 the resistance offered by the air gap and consequently for varying the maximum load to be placed upon the interposed block of material. 55

In testimony whereof I have affixed my 60 signature in the presence of two witnesses.

LEON S. BRACH.
